UNITED STATES PATENT OFFICE.

CHARLES BURTON HOWD, OF CHICAGO, ILLINOIS, ASSIGNOR TO SAHLIN CORSET COMPANY, OF CHICAGO, ILLINOIS, A CORPORATION OF ILLINOIS.

GARMENT-CLOSURE.

SPECIFICATION forming part of Letters Patent No. 695,895, dated March 11, 1902.

Application filed December 30, 1901. Serial No. 87,711. (No model.)

To all whom it may concern:

Be it known that I, CHARLES BURTON HOWD, a citizen of the United States, and a resident of Chicago, in the county of Cook and State of Illinois, have invented certain new and useful Improvements in Garment-Closures, of which the following is a full and complete specification, reference being had to the accompanying drawings, forming a part thereof.

The purpose of this invention is to provide an improved formation of apertures for lacing or hook eyelets or buttonholes in garments, and particularly in the formation of such apertures and the adjacent structure of the edges which are laced together in corsets, waists, and other like undergarments.

Heretofore the apertures for lacing in garments have been usually reinforced by one of three methods: (a) metal eyelets, (b) buttonhole-stitching, (c) binding-tape. The first method is objectionable both on account of the appearance and insecurity, and especially on account of the danger of rusting the goods. The other two methods are objectionable on account of the expensiveness, and the third also on account of clumsy appearance. My improvement dispenses with all of these methods and provides an aperture of ornamental appearance which is bounded by folded edges of the fabric and in the specific structure in which it is used in corsets is fortified on the side on which the strain it is exposed to and wear of lacing by the metal stay which forms the edge.

My present invention further consists, specifically, of a structure at the laced edges of the corset or like garment by which the lacing is protected and the gap spanned by lacing is closed or concealed.

In the drawings, Figure 1 represents two edges, as of a corset, provided with my invention and laced together. Fig. 2 is an elevation of a sample lacing edge, showing at the upper part one form and at the lower part a slightly-modified form of applying my invention, the binding or covering and securing strips being partly cut away and folded back to disclose the detail structure more fully. Fig. 3 is a view similar to Fig. 2, showing a modified form of the eyelet-forming strip.

Fig. 4 is a detail plan of the eyelet-forming strip of the form shown in Figs. 1 and 2. Fig. 5 is a similar detail showing a slight modification which may be made in the use of said strip.

I will describe my invention as applied to the back junction of a corset-body, which is customarily laced together along the spine; but it should be understood that while certain details of structure are especially designed in view of a laced junction at this position the invention broadly is not limited to any particular position nor to any particular style of garment.

A may represent the body of the garment, the fabric being shown double, as is customarily the case, the inner ply of the fabric being extended beyond the laced edge and folded at a back upon itself to form a fly A' under the lacing. For the purpose of producing the apertures for lacing I use in the form of my invention shown in Fig. 1 a strip B of fabric, usually the same as that of which the body of the garment is made. This strip preferably has both lateral edges folded under, the fold being creased down, and the strip is then folded, as seen most clearly in Fig. 4, forming right-angular points B², projecting both ways from the middle line of the resultant zigzag strip, each point being made by folding the strip upon itself at an angle of forty-five degrees, two such folds constituting a pair making a right angle with each other at one lateral edge, the next two folds similarly making a right angle with each other at the other lateral edge, the adjacent folds of consecutive pairs being parallel, and the distance between such parallel folds being as much greater than the width of the strip as the length of the lacing-aperture which is to be produced in the mode of use of the strip which is seen in the upper part of Fig. 2. In all the forms illustrated the zigzag strip which results from such folding is bound at one edge in the binding C, which makes the sheath for the stay or "bone" D, the points at the side of the zigzag thus bound being entirely inclosed with the said stay in such binding-sheath. If the stay or bone is less in width than the strip used in making the zigzag and if, therefore, the points of the zigzag are higher

than can be completely inclosed in such binding without doubling them, they may be clipped—that is, the angle may be cut off—as seen at b^2 , Fig. 5. The other side of the 5 zigzag strip is secured on the outer face of the body A, being preferably covered and having its points completely inclosed by a felling-strip E, which is simply a strip of the fabric having both lateral edges folded under and stitched down at the folded edges and, if desired for appearance, having a third line of stitching at the middle of the width. The zigzag strip is thus mounted on the body and covered, as described, at a sufficient distance back from the folded edge a , leaving a proper width of fly A' projecting under the lacing edge, which is the stay-strip D, and beyond such edge such distance as may be deemed necessary to meet a corresponding 15 fly from the opposite edge and form a backing for the lacing, which spans the aperture from side to side. It will be observed that this structure leaves between each two adjacent edges of the strip which is folded to make 20 the zigzag a rift b' , whose length is the excess of the distance measured on the edge of the strip between the parallel folds $b^3 b^3$ (see Fig. 4) over the width of the strip. These rifts constitute the apertures for the lacing, and it will 25 be noticed that their lateral edges are formed by folds of the fabric and that their ends, although until they are spread by use they have no sensible width, are also formed by folded edges, and however much they may stretch 30 in use they will still be guarded on all four sides by folds of the fabric. A preferred form of eyelet may be produced by the use of strips folded in precisely a similar manner, but having the bound stay, which forms the 35 guard at the side on which the lacing draws, applied so that the binding of said stay takes 40 in the points B^2 , not for their whole depth, but to a distance which leaves a small triangular aperture b^4 , as seen in Fig. 1 and at the 45 lower part of Fig. 2, one side of said triangle being parallel with the stay and, in fact, being formed by the binding which incloses the stay. This form of eyelet is somewhat more 50 attractive in appearance, and it has the special advantage that the lacing draws, not into an angle or crevice, which is liable to cause it to be drawn into a string, but over an edge corresponding to the width of such lacing, so 55 that it is easily kept flat and is less liable to be chafed in use.

A somewhat similar formation of a strip to serve the purpose of a zigzag strip above described is shown in Fig. 3. In this form a narrow strip of the fabric having both edges 60 folded under at the same side and preferably meeting, so as to make the strip practically double, and having folded edges at both sides is folded into a zigzag, as clearly seen at the lower part of Fig. 3, all the folds by which the 65 zigzag is produced being made in the same direction and at an oblique angle—that is, not directly across the strip—thus leaving at

both sides indentations or recesses B^3 . This zigzag is then bound in at one side to the binding inclosing the stay-strip, said binding 70 taking in something less than the full depth of the acute notch, leaving exposed a small triangular portion at the apex of the notch, the oblique folds at the other side of the zigzag strip being covered under the felling-strip E in the same manner as above described.

I do not limit myself to using the fabric of which the garment is made or any fabric requiring to be cut in strips and folded, but, on the contrary, tape may be used to form the zigzag strips in whichever of the forms shown they are to be made or applied. For some purposes it may not be considered necessary even to provide the strip with folded edges, 85 and in the form shown in Fig. 1 it will be noticed that the sides of the triangular apertures will be folds of the strip, even though the strip be not first formed, as described, by having its lateral edges folded under, since 90 the sides of these triangular apertures are formed by the folds made at forty-five degrees across the strip in producing the zigzag.

The fly A' may have inserted in it at the option of the wearer a stiffening or a padding strip, which may be withdrawn when not desired. Such strip is shown in Fig. 2 protruding at the lower end, (denoted by the letter F.) This may be taken as representing either 95 stiffening or padding. If an additional stay or bone is desired, it may be inserted in the same manner in the folded edge of the fly.

I claim—

1. A closure for garments, comprising a flat strip of tape or fabric folded obliquely on 105 itself to cause each lateral edge to cross only the opposite lateral edge without crossing itself, and a band secured across the oblique folds at one side of such folded strip, the other side being secured to the main part of 110 the garment.

2. A closure for garments comprising a flat strip of tape or fabric folded obliquely on 115 itself to cause each lateral edge to cross only the opposite lateral edge without crossing itself, a band secured across the oblique folds at one side of such folded strip, and means 125 attached to the opposite side for securing such obliquely-folded strip to the main part of the garment.

3. A closure for garments comprising a strip of fabric folded obliquely upon itself back and forth across the line of the holes or eyelets to cause each lateral edge to cross only the opposite lateral edge without crossing 125 itself forming a zigzag; a band secured across the projections of the zigzag at one side of the line of the holes; and means for securing the projections at the other side to the garment.

4. A closure for garments formed by a strip of fabric folded obliquely upon itself to cause each lateral edge to cross only the opposite lateral edge without crossing itself, the ob-

lique folds being in pairs, the two of each pair being at right angles, and consecutive pairs having the adjacent folds parallel; whereby a zigzag tape is formed combined with a band secured across the lateral projections of the zigzag at one side; and means for securing those at the other side to the garment.

5 5. A closure for garments formed by a strip of fabric folded obliquely on itself to cause each lateral edge to cross only the opposite lateral edge without crossing itself; a binding spanning the angular notches which result from such folding and infolding the outer portion of the edges thereof; whereby triangular openings are left at the apex of the notches; and means for securing the opposite oblique folds to the garment.

10 6. A closure for garments formed by a strip of fabric folded obliquely on itself to cause each lateral edge to cross only the opposite edge without crossing itself producing a zigzag; a binding infolding the projections of the zigzag at one side; a stay or "bone" also infolded in such binding, the projections of

the opposite side of the zigzag being secured 25 to the garment.

7. A garment having a lacing edge comprising an eyelet-fly formed by a strip of fabric folded obliquely upon itself to cause each lateral edge to cross only the opposite edge without crossing itself forming a zigzag; a binding infolding the zigzag projections at one side, the other side being secured upon the face of the garment at a distance back from the edge greater than the width of the eyelet- 30 fly and its binding; whereby the edge portion of the garment constitutes a fly projecting beyond the bound edge of the eyelet-fly under the lacing.

15 In testimony whereof I have hereunto set 40 my hand, in the presence of two witnesses, at Chicago, Illinois, this 28th day December, A. D. 1901.

CHARLES BURTON HOWD.

In presence of—

HERBERT J. ADAMS,
HAROLD WARNER.
